UNITED STATES PATENT OFFICE.

JONAS MATULAITIS, OF SCRANTON, PENNSYLVANIA.

STREET-CAR SWITCH.

1,294,508.

Specification of Letters Patent.

Patented Feb. 18, 1919.

Application filed May 3, 1918. Serial No. 232,330.

To all whom it may concern:

Be it known that I, JONAS MATULAITIS, a citizen of Russia, residing at Scranton, county of Lackawanna, and State of Pennsylvania, have invented certain new and useful Improvements in Street-Car Switches, of which the following is a specification.

This invention relates to improvements in railway devices and has as its special object the provision of means, operable from a car, by which a switch point or tongue, may be operated in either direction so as to cause the car to traverse along the main track or be diverted to a branch or siding.

A further object is to provide means, carried by and readily operable from the car without dismounting therefrom.

These and other like objects are attained by the novel construction and combination of parts hereinafter described and shown in the accompanying drawing, forming a material part of this specification, and in which:—

25 Figure 1 is a fragmentary plan view showing a section of track and car thereon.

Fig. 2 is a sectional view taken on line 2—2 of Fig. 3.

30 Fig. 3 is a front view partially in section illustrating the application of the invention, and

Fig. 4 is a transverse sectional view taken on line 4—4 of Fig. 1.

In the drawing, the numeral 10 designates 35 a conventional type of car, 11 and 11' the running rails thereof, and 12 and 12' the switch points respectively, the same resting upon the ties in the ordinary manner.

40 Adjacent to the switch is a casing, the lower flange 14 of which is secured to the ties, the upper flange 15 being connected integrally thereto by a vertical element 16. This casing is preferably formed with a V shaped front 17 so as to guide the operating 45 means in a manner which will be farther on described.

The switch points 12 and 12' are connected near their front end with a rigid transverse bar 20 which has secured to it 50 angle irons 21 arranged in opposed pairs, the inner faces of the angle irons having riveted to them vertically positioned longitudinal bars 22 and 22', the same extending toward the front and being engaged 55 between the elements 14 and 15 of the cas-

ing, being pivoted therebetween, upon pins 23 and 23' as best shown in Fig. 1.

Secured upon the floor of the car 10, in the forward motorman's compartment, is a bracket 25 in which, pivoted upon the pins 60 26, are levers 27 having extending operating handles 28, and engaged by pins 30 are depending bars 31 and 31' the same extending downward through the floor of the car.

Secured to the bars 31 and 31' are outstanding lugs 32 adapted, when in a raised position, to be supported by the flat ends of plates 33 pivotally secured to the bottom of the car by pins 34, and having finger grips 35 at their opposite ends for turning 70 the flat portion or ends of the plates 33 underneath of the lugs 32 for locking the bars 31 and 31' or unlocking the same when the ends of the plates 33 are turned away from underneath of the lugs 32. 75

At the end of the car below the floor is a rigid support 38, having outwardly projecting wing-like elements 40, their lower surfaces being beveled and adapted to make contact with projections 42 and 42' rigidly 80 engaged with the bars 31 and 31' the upper portion of the elements 42 and 42' being also beveled to make contact with the outstanding wings, so that when raised they are caused to separate, as best shown in 85 Fig. 3.

The bars 31 and 31' are normally constrained toward the rigid support 38 by means of coiled tension springs 43 between the respective bars, while at the extreme 90 lower end of the bars 31 and 31' are journaled rollers 44 and 44' upon vertical axes and arranged so that their peripheries can make contact with the outer surface of the bars 22 and 22'. 95

In operation, the switch being positioned as shown in Fig. 1, and it is desired to direct the car to the siding, it is necessary to move the switch point 12 out of engagement with the rail 11, and move the oppositely disposed switch point 12' toward the rail 11' which is accomplished in the following manner. The plates 33 being removed, the handle 28 is depressed as in Fig. 3, lowering the bar 31', so that the roller 105 44' comes in contact with the vertically disposed bar 22', the spring 43 acting to move the bars laterally and hence move the cross bar 20, connected with the switch points, so as to allow the car to enter upon the siding 110

and it will be obvious that by operating the lever, such result may be obtained.

These devices can be applied at each end of the car, so that when moving in either 5 direction the switches may be thrown in the proper manner by the person in charge of the car.

Having thus described my invention what 10 I claim as new and desire to secure by Letters Patent, is:

15 In a device for the operation of a railway switch from a moving car, the combination of a bracket secured to the bottom of the car, levers pivotally secured in said bracket operating handles on said levers, vertical bars secured to said levers and passed through the car bottom, outstanding lugs secured to the outer sides of said bars, lock-

ing plates pivotally secured to the car bottom near said bars adapted to be turned in and out of engagement underneath of said lugs, a rigid support secured to the lower face of the car bottom, outwardly projecting beveled wings on the lower ends of said supports, inwardly directed beveled projections on said bars below the bottom of said car, adapted to contact with said beveled parts of the wings, springs for normally constraining said bars toward said support, and rollers journaled to the lower extremities of said bars and adapted to operate the points of a switch.

20 25 30 In testimony whereof I have affixed my signature.

JONAS MATULAITIS.
